(57) CLAIM

The ornamental design for a scale, as shown and described.

DESCRIPTION

FIG. 1 is a top and side perspective view of a scale showing my new design;

FIG. 2 is a top plan view thereof;

FIG. 3 is a view thereof from the bottom of FIG. 2, the view thereof from the top of FIG. 2 being identical thereto;

FIG. 4 is a view thereof from the right of FIG. 2, the view from the left of FIG. 2 being identical thereto;

FIG. 5 is a bottom and side perspective view thereof; and,

FIG. 6 is a bottom plan view thereof.

The top plate of the scale is transparent.
